Atty.

UNITED STATES PATENT OFFICE.

FRANCIS EDWIN ARMSTRONG, OF TORONTO, ONTARIO, CANADA.

ADVERTISING MEDIUM.

Application filed February 11, 1924. Serial No. 691,946.

To all whom it may concern:

Be it known that I, FRANCIS EDWIN ARMSTRONG, a subject of the King of Great Britain, residing in the city of Toronto, 5 county of York, Province of Ontario, Canada, have invented certain new and useful Improvements in Advertising Mediums, of which the following is a specification.

My invention relates to improvements in advertising mediums, and more particularly to outdoor means for displaying advertisements, and the objects of my invention are, first, broadly, to produce a non-fragile advertising medium assembled or manufactured within doors, which will be strong and flexible in character so that it may be folded or rolled for transportation to place of use, and then opened out and readily mounted by unskilled labor; second, specifically, to produce a medium possessing the characteristics set forth which will permit light rays to pass therethrough to clearly display the advertising matter, and third, to provide an outdoor advertising medium less costly to manufacture, install, and use, than any I am acquainted with thereby placing within the reach of many advertisers, locations now only possible to rent by those whose appropriations are very large, and in the following specification I shall describe and disclose several embodiments within my invention, and what I claim as new will be set forth in the claims forming part of this specification.

Fig. 1 is a front elevation of a display medium within my invention, unmounted, showing the advertisement-medium carrying member co-extensive with the backing or foundation. Fig. 2 is a view similar to Fig. 40 except that the advertisement-carrying member is composed of several sections coupled together. Fig. 3 is a plan view of a circular frame showing my advertising medium removably coupled thereto in a convenient manner, and Fig. 4 is a front elevation of portion of my preferred form of advertising medium showing the backing or foundation, and showing the preferred manner in which the over-lapping ends of

the advertisement-carrying member are 50 secured in place.

In the drawings, like characters of reference, refer to the same parts.

Obviously since my advertising medium may be readily mounted in place of use, it 55 may be readily demounted when it is desired to change the advertisement.

The backing or foundation for my advertising medium may be made of any suitable flexible material, adapted to be manipulated as set forth, and which will weather a reasonable length of time, and this backing or foundation may be made of vegetable or mineral matter, for instance, such as canvas or duck, and wire netting, either in woven 65 or otherwise built-up form.

Although the advertising medium in its preferred form will preferably permit light rays to pass therethrough so that a source of light located within or behind the article 70 may illuminate the advertising matter, it must be distinctly understood that I do not confine myself to constructing my advertising medium to permit light rays to pass therethrough, nor do I confine myself to any 75 particular mounting means or support for the advertising medium, nor to any particular way or manner of detachably securing the advertising medium to its frame or support.

Nor do I confine myself to any particular means of detachably securing the advertisement-carrying member to the flexible backing or foundation.

Although I have shown the advertisement-carrying member in the form of a covering substantially co-extensive in size with the backing or foundation, it must be understood that the relative position of these parts can be inverted; that is to say, the 85 printed, lithographed, or painted surface of the advertisement-carrying member may be placed against the back of the backing or foundation, and the mesh of the latter may be large enough to permit the advertisement 90 to be read therethrough, particularly if a source of light be located within or behind the advertising medium.

A is any suitable flexible backing or foundation which will reasonably withstand the weather and wind pressure, and suitably removably secured to said backing or foundation is the flexible advertisement-carrying member B which may be made of any suitable mineral or vegetable substance, opaque, or not.

In Figs. 1 and 2 I show a conventional form of advertisement with which the advertisement-carrying member B is provided. This member is suitably removably secured to its backing or foundation A, and my preferred manner of coupling these parts together is by means of stitching C. This stitching material may be of mineral or vegetable substance. I prefer to use weather-proofed linen or cotton for this purpose, such as bootmakers use.

20 The article in question may be coupled to any suitable support either flat, circular or otherwise shaped, and a convenient way of preparing said article for attachment is to provide the same with a plurality of holes 25 D along each side and end through which fastening means may be passed.

In Fig. 2 the advertisement-carrying member B is shown as composed of several sections E, and these sections will be associated 30 with their backing or foundation A to properly display the advertisement.

The form of the articles shown in Figs. 1 and 2 may be secured to a flat surface, or they may be secured around a circular frame 35 composed of a plurality of hoop-shaped members F. These members are properly braced together, and otherwise supported, but as this bracing and supporting is not germane to my invention I have not illustrated 40 same.

45 The size of the advertisement of course will determine the size of the backing or foundation A. When the size of the sign has been decided on, the advertisement-carrying member B is removably secured to its 50 backing or foundation in the factory or workshop and in due course the article is folded or rolled for transportation to point of use.

55 When the article is provided with the holes D, suitable fastening means must be passed therethrough, such as bolts G which may be permanently mounted in the supporting member for the article, such as the hoops F, one only of which is shown in Fig. 3. The 60 holes D will be made to register with the bolts G, and when the article has been placed in position, the nuts H are replaced.

In order to prevent the wind injuring the 65 advertisement-carrying member B, the edge I of the outer end J of the advertisement-carrying member B is preferably over-sewn by means of stitches K. Of course any other suitable destructible fastening for this purpose may be used.

In order to allow for expansion and contraction and to reduce to a minimum distortion of the article, the slots 2, as well as the holes D are so formed as to provide for the necessary movements.

70 In Fig. 3 a source of light 3 is shown in the form of an electric lamp which is located within the support for the advertising medium, and when the backing or foundation A and advertisement-carrying member B will permit the passage of light rays therethrough, the advertising matter will be illuminated. This will make a very attractive advertising device, specially if the mounting frame therefor be moved or rotated.

75 When my advertising medium is attached to a wooden wall, either indoors or outdoors, the advertisement-carrying member B need not necessarily be made of material to permit light rays to pass therethrough, because 80 in this field of use interior or rear lighting of the sign is not sought.

85 Where the space is quite large, of course the advertising matter of various manufacturers and merchants can be displayed on 90 one sign. In such a case, if any given contract for portion of the area of such sign should not be renewed, the advertisement-carrying area can be readily removed without demounting the sign, and replaced.

95 It must be understood that the outer end J will be secured in place after the circular sign has been mounted, as well as the overlapping ends 4 of the backing or foundation A.

100 While I have described what I consider to be the best embodiment within my invention, it must be understood that the principle thereof may be embodied in many different forms, and I desire not to be limited beyond 105 the requirements of the prior art and the terms of my claims.

What I claim is:

1. As a new article of manufacture, a laminated advertising medium of flexible sheet formation comprising a weather and wind-proof light passing backing layer, a weather and windproof advertisement carrying layer coextensive with the backing layer and formed of light passing material, and means for connecting the layers along spaced lines which are distributed over the entire area of the medium whereby slight relative movement of the layers between said lines will be permitted when the medium is folded or rolled.

110 2. As a new article of manufacture, a laminated advertising medium of flexible sheet formation comprising, a weather and wind-proof light passing backing layer, a weather and wind-proof advertisement carrying layer coextensive with the backing layer and formed of light passing material, said advertisement carrying layer being 115 formed of a plurality of interconnected sec- 120

tions adapted to carry related or unrelated advertising data, and means for connecting the sections of the advertisement carrying layer to the backing layer along spaced lines so that the said layers will be permitted to move relative to each other between said spaced lines when the medium is folded or rolled and so that said sections may be independently disconnected from the other sections and the backing layer without being destroyed for being replaced by additional sections carrying different advertising data. 10

FRANCIS EDWIN ARMSTRONG.
